UNITED STATES PATENT OFFICE.

CALEB CUSHING ADAMS, OF BROOKLYN, NEW YORK.

DESIGN FOR A SPOON, &c.

SPECIFICATION forming part of Design No. 21,460, dated April 12, 1892.

Application filed September 12, 1891. Serial No. 405,539. Term of patent 7 years.

To all whom it may concern:

Be it known that I, CALEB CUSHING ADAMS, a citizen of the United States, residing in Brooklyn, in the county of Kings and State 5 of New York, have invented and produced a new and original Design for Spoon and Fork Handles; and I do declare the following to be a full, clear, and exact description of the same, reference being had to the accompanying drawings, forming a part thereof.

Figure 1 is a view of one side of the handle, and Fig. 2 is a view of the other side.

The leading features of my design consist in a representation of the New York and Brooklyn bridge upon one side of the handle and a picture of an old church in the bowl of the spoon or upon the flat part of the fork in rear of the tines thereof and upon the reverse side of the handle a representation of the original ferry between New York and Brooklyn, and upon this side of the handle also appear the words and figures "Breuckelen, 1667. Fulton Ferry, 1746," and upon the other side

of the handle are the words "The Brooklyn Church, 1776. Brooklyn Bridge, 1883," and 25 within the bowl of the spoon are the words "City of Churches;" but such words and dates form no part of my invention.

Referring to Fig. 1, A represents the original ferry-boat, and B B B represent certain 30 old buildings, which in primitive times were adjacent to the original Brooklyn ferry.

In Fig. 2, C C indicate the towers of the New York and Brooklyn bridge; D D indicate the bridge structure, and E indicates the old 35 church.

I claim—

The design for spoon and fork handles, herein shown and described.

In testimony whereof I affix my signature in 40 presence of two witnesses.

CALEB CUSHING ADAMS.

Witnesses:

PHILLIPS ABBOTT,
D. S. RITTERBAND.
